(57) **CLAIM**

The ornamental design for a storage bin latch assembly, as shown and described.

DESCRIPTION

FIG. 1 is a perspective view of a bin latch embodying our new design;

FIG. 2 is a front elevational view thereof;

FIG. 3 is an end elevational view thereof;

FIG. 4 is a side elevational view thereof; and,

FIG. 5 is an alternative front elevational view thereof.

The broken line showing is for illustrative purposes only and forms no part of the claimed design.

1 Claim, 2 Drawing Sheets

FIG. 3

FIG. 2

FIG. 1

FIG. 5

FIG. 4
